UNITED STATES PATENT OFFICE.

ALBERT BEYLER, OF MANNHEIM-NECKERAU, GERMANY, ASSIGNOR TO RHEINISCHE GUMMI- UND CELLULOID-FABRIK, OF MANNHEIM-NECKERAU, GERMANY.

DOLL EYES.

Application filed May 27, 1927, Serial No. 194,801, and in Germany May 31, 1926.

This invention relates to dolls' heads, for so-called "sleeping dolls," and particularly to the arrangement of the mechanical eyes thereof.

5 It has hitherto been the practice to make these eyes by turnably supporting connected eyeballs in gypsum supports provided on the inside of the head and allowing said eyeballs to swing by the aid of a weight eccentrically mounted on the connecting member so that, when the doll is laid down, the iris of each eyeball disappears and a flesh-tinted coat of paint appears in its place in the orbit. These customary mechanical eyes exhibit various defects, especially that of closing in an unnatural manner; they are easily liable to damage; and the gypsum supports, situated laterally in relation to the orbit show up, in a patchy or shadowy form, 20 through the celluloid or other translucent material of which the doll's head is made. There is also a risk of the pivotable parts becoming jammed in the supports.

Other mechanical eyes are also known in which the eyeballs are stationary whereas imitations of the eyelids are connected together by a stay, which is either mounted in special bearings on the head or bears (by means of its concave outer ends) against the mutually facing sides of the eyeballs. This arrangement, however, is difficult to mount and is particularly liable to jam.

35 This invention avoids all the defects of known arrangements in that use is made of conchoidal eyelids formed of thin, light and elastic material moulded to hallow or substantially semi-spherical shape and loosely surrounding or mounted on the eyeballs which latter are fixed and serve as pivots for 40 the lids. The two hollow or semi-spherical eyelids are preferably connected together by a light stay or bridge to the centre of which is attached a small eccentric weight. In the front side of each eyelid a narrow 45 gap is provided in shape corresponding with the eye orbit in the doll's head and said gap is so disposed that when the doll is in upright position, the iris is visible through the orbit. As the eyelid unit for both eyes is 50 extremely light, and as the actuating weight can also be made very light, the eye structure cannot easily become damaged by shock, for example when the doll is allowed to fall.

The invention also provides for adjustably securing the eyeballs in the head of the doll in a manner to serve as bearings for the lids, so that no lid fastenings will be visible from the outside.

55 In order that the invention may be clearly understood, reference will now be made to the accompanying drawings, which typically illustrate the invention in diagrammatical form as applied to a doll's head made of celluloid or the like.

60 Fig. 1 is a side elevation of the doll's head, partly in section;

65 Fig. 2 is a front elevation of the same;

Figs. 3 and 4 are detail views, on a larger 70 scale, showing the eyes with the movable eyelids in open and closed positions respectively with the head in vertical and horizontal inclination;

75 Fig. 5 is a plan of the means for securing the eyeballs in place, the doll's head being omitted; and

Fig. 6 is a perspective view of the eyelids prior to being placed on the eyeballs, the pendulum weight being omitted.

80 In the drawing, *a* represents the doll's head provided with the eye orbits *b*; *c* is a crossbar fixed in the head and having a longitudinal slot *d*, in which small rods or wires *e* are adjustably secured by means of nuts *g* and washers, while *f* denotes the 85 glass eyes of the usual type, attached to the front ends of the wires.

85 The eyeballs are adjusted on the crossbar *c* so that the distance between their centres corresponds to the distance between the 90 centres of the orbits *b* in the head *a*.

95 Reference *i* denotes the eyelid-members formed of thin elastic material such as celluloid moulded to hollow shell or socket form which (as shown more particularly in Figs. 3-5) are slightly more than hemispherical in shape and have an internal diameter slightly larger than the external diameter only of the spherical eyeballs *f*. These shells or calottes constituting the eyelids, have gaps *k* corresponding in size and shape to the eye orbits *b*. A small bridge-rod or thin tube *l*, preferably of celluloid or the like, connects the two shells or eyelids *i* together in such manner that the distance 100 between their centres corresponds to that of the eyeballs *f*. The unit composed of the two shells *i* and the bridge *l* (shown separately in 105

Fig. 6) is slipped engageably over the eyeballs *f* fastened to the crossbar *c*. Owing to the thinness and elasticity of the material of which the shells *i* are made, it is usually possible to slide or snap them over the eyeballs by exerting a fairly strong pressure, whereupon, they remain so secure that there is no risk of their afterwards becoming detached. This is due to the fact that the eyelid members cover more than a hemispherical portion of the eyeballs.

As indicated in the drawing, the unit composed of the two shells *i* and the bridge *l* may also be made in two parts which can be connected together when in position on the eyeballs. In any event, when assembled, the hollow semi-spheres *i* surround the eyeballs so as to be easily rotatable thereon without any risk of becoming detached.

20 A small pendulum weight *m*, of lead or the like, is eccentrically attached to the bridge *l* by means of a small rod *n*, which may be of wire or celluloid. *o* are eyelashes attached to the inside of the shells *i*.

25 The eye structure assembled in the manner described can be securely fixed to the head by means of the bar *c*, the latter being disposed crosswise of the head. The example shows a particularly suitable method 30 of attachment to the head, use being made of an inwardly bent edge or flange *a*¹ at the opening provided in the back of the head, which opening is eventually concealed by the hair. For this purpose, the bar *c* is provided at both ends with slots *c*¹ which grip the edge *a*¹. In this manner the bar can be securely attached to a head, even when the latter is made of thin material, such as celluloid, and it can be fixed in position by any 35 known means, such as glue, celluloid solution or the like.

It will be seen that the eyeballs *f* are set or adjusted at such a distance from the face side of the head *a* as to leave, between the 45 orbits *b* and eyeballs *f*, a narrow slit in which the eyelids *i* can move freely. When the doll's head is inclined from the position shown in Fig. 3, the thin eyelids gradually close over the fixed irises and pupils, so that 50 there is no change in the position of the eyes, which are accordingly closed in a life-like manner.

Having now fully described my invention, what I claim and desire to secure by 55 Letters Patent is:—

1. In a doll's head, an eye structure comprising eyeballs held in fixed position within the head contiguous to eye orbit openings formed in the face of the latter; 60 thin semi-spherically formed eyelids loosely engaging over the eyeballs in substantial encompassment thereof and having gaps exposing the iris portions of said balls, and means acting to maintain the eyelids always in the same vertical position.

2. In a doll's head, an eye structure comprising eyeballs held in fixed position within the head contiguous to eye orbit openings therein so as to leave a slight space between said balls and the front face of the head; 70 eyelid-members in the form of semi-spherical sockets engaging over said eyeballs for more than a hemispherical portion thereof so as to be pivotally movable thereon within said space; means connecting the eyelids for unitary movement; and means acting by gravity to maintain the eyelids always in the same vertical position.

3. In a doll's head, an eye structure comprising eyeball-members; means supporting 80 said members from the back of the head in fixed position behind eye orbit openings therein so as to leave a slight space between said members and the front face of the head; eyelid-members in the form of thin 85 partly-spherical sockets engaging over the greater portions of the eyeball-members so as to be supported and pivotally movable thereon, a bridge-member connecting the eyelids; and a weight suspended from said 90 bridge-member.

4. In a doll's head, an eye structure comprising a bar bridging the opening in the back of the head over which the hair is attached, a pair of rods extending forwardly 95 from the bar, two eyeballs fixed one on the forward end of each of said rods adjacent the eye orbits in the head, eyelids in the form of thin partly-spherical sockets pivotally supported on the eyeballs, a cross bar connecting the eyelids, and a weight suspended 100 from the crossbar.

5. In a doll's head, an eye structure comprising a slotted bar bridging the opening in the back of the head over which the hair is attached, a pair of rods adjustably secured 105 in the slot in the bar and extending forwardly from the bar, two eyeballs fixed one on the forward end of each of said rods adjacent the eye orbits in the head, eyelids in the 110 form of thin partly-spherical sockets pivotally supported on the eyeballs, a crossbar connecting the eyelids, and a weight suspended from the crossbar.

6. In a doll's head, an eye structure comprising a slotted bar bridging the opening in the back of the head over which the hair is attached, a pair of rods adjustably secured in the slot in the bar and extending forwardly from the bar, two eyeballs fixed one 115 on the forward end of each of said rods adjacent the eye orbits in the head, eyelids in the form of thin partly-spherical sockets pivotally supported on the eyeballs, said eyelids having apertures conforming to the 120 eye orbits in the head, a crossbar connecting the eyelids, and a weight suspended from the crossbar.

7. In a doll's head, an eye structure comprising a slotted bar bridging the opening 125

in the back of the head over which the hair is attached, a pair of rods adjustably secured in the slot in the bar and extending forwardly from the bar, two eyeballs fixed 5 one on the forward end of each of said rods adjacent the eye orbits in the head, eyelids in the form of thin partly-spherical sockets pivotally supported on the eyeballs, said eyelids having apertures conforming to the eye 10 orbits in the head, eyelashes attached to the eyelids adjacent the edges of the apertures, a crossbar connecting the eyelids, and a weight suspended from the crossbar.

8. As a new article of manufacture for 15 use in so-called sleeping dolls, a movable eyelid structure consisting of a pair of substantially semi-spherical socket members of thin elastic material snap-engaged on and movable over the doll's eyeballs and an in-

tegral connecting bridge therefor. 20
9. As a new article of manufacture for use in so-called sleeping dolls having fixed eye ball members in the head portion thereof, a movable eyelid structure consisting of a pair of substantially hemispherical socket mem- 25 bers of thin elastic material held in snap-engagement with said eyeball-members and having an integral bridge member connecting them together for unitary movement, said socket members being formed with gaps 30 conforming to the eye orbit openings in the face of the head and being movable upon the eyeball-members with their gaps into and out of registration with said openings.

In testimony whereof I have affixed my 35 signature.

ALBERT BEYLER.
